(57) **CLAIM**

The ornamental design for a packaging container, as shown and described.

DESCRIPTION

FIG. 1 is a front elevational view of a packaging container showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a perspective view thereof;

FIG. 7 is a cross-sectional view thereof, taken along line 7-7 of FIG. 1;

FIG. 8 is a cross-sectional view thereof, taken along line 8-8 of FIG. 1;

FIG. 9 is a cross-sectional view thereof, taken along line 9-9 of FIG. 2;

FIG. 10 is a cross-sectional view thereof taken along line 10-10 of FIG. 2; and,

FIG. 11 is a perspective view thereof, shown in a stacked condition in environmental use.

The broken lines of the container of FIG. 11 illustrate environmental subject matter that forms no part of the claimed design.
